(57)

CLAIM

I claim the ornamental design for a pet nail grinder, as shown and described.

DESCRIPTION

FIG. 1 is a Perspective view of a pet nail grinder showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

(Continued)

FIG. 7 is a Bottom view thereof; and,
FIG. 8 is other perspective view thereof.

1 Claim, 7 Drawing Sheets
